PIPE REAMER

Henry H. Giles, Pittsburgh, Pa.

Application November 6, 1946, Serial No. 708,110

17 Claims. (Cl. 131—232)

1

This invention relates to a mechanical reamer for tobacco pipes.

The object of the invention is to provide a pipe reamer which gives a mechanical reaming action in the bowl of the pipe, with a minimum of mechanical parts and with simplicity of mechanical structure, while performing its intended function under the influence of simple and easy manual operation.

Another and conjoint object is to provide a pipe reamer of the designated sort which comprises means for receiving ashes, dottle and crust removed from the bowl of a pipe, and which reamer assembly is as a whole of pleasing appearance.

In the accompanying drawings illustrative of my invention:

Fig. I is a plan view of a pipe reamer constituting a simple embodiment of my invention.

Fig. II is a vertical sectional view through the reamer taken in the plane of the section line II—II of Fig. I.

Fig. III is a plan view of a modified form of the reamer.

Fig. IV is a vertical sectional view through the reamer taken in the plane of the section line IV—IV of Fig. III.

Figs. V, VI and VII are vertical sectional views of further modified forms of the reamer.

In the accompanying drawings reference numeral 1 designates a relatively deep dish, which serves as a mounting base for the mechanical elements of the reamer and as a receiver for ashes and dottle from tobacco pipes in the bowls of which the reamer acts. Secured in the bottom of dish 1 there is an upright post 2, which desirably is mounted centrally of the dish, as shown, and which houses a spindle 3. Convenient means for mounting post 2 in dish 1 are shown as a nut 2a on a threaded extension 2b of post 2 and bearing against a washer 2c on the under surface of the dish. A horizontal tool-carrying arm 4 is mounted on spindle 3, being shown as secured thereto by means of a cap 5 threaded at 6 to the upper region of the spindle. The ball 7 shown in Figs. I and II as mounted on tool-carrying arm 4 is purely ornamental.

The reaming tool 8 is of a form usual in pipe reamers, desirably having a double cutting thread 8a. This reaming tool 8 is non-rotatably mounted on horizontal arm 4 in a position substantially removed from the vertical pivot provided by spindle 2. This eccentric mounting is such as to cause reaming tool 8 to move through a circular path of substantial radius when carrying arm 4 is rotated.

2

In use of the reamer, the bowl of a pipe is placed in an inverted position on reaming tool 8 so that the tool enters or tends to enter the cavity of the bowl. The stem of the pipe being firmly held by the user, he provides a simple crank motion by movement of his own arm to produce rotation of the tool-carrying arm 4 by contact of the pipe bowl with the tool. The pipe being held firmly there is then a single complete relative revolution of the reaming tool and the pipe bowl for each revolution of the tool-carrying arm. As this action proceeds the reaming tool dislodges dottle from the pipe bowl, and may scrape the crust surrounding the cavity in the bowl to limit the thickness of such crust. Particles of dislodged dottle and scraped crust, together with any ashes which may be in the pipe bowl, fall into dish 1.

In order to make sure that such particles are not flung outwardly beyond the dish in rapid rotational movement of the reaming tool, it is desirable to provide collecting means surrounding the tool. Such means are shown as a cup mounted on tool-carrying arm 4 around the reaming tool. The cup has a peripheral wall 9 which serves as a guard against the dispersion of refuse from the pipe bowl and a bottom having there-in relatively large openings 10 for the discharge of refuse from the pipe into the underlying dish. The grid 11 shown in Figs. I and II of the drawings is a desirable adjunct to the reamer assembly because it provides an ornamental screen preventing accidental contact with refuse received in the dish from the pipe bowl which is being cleaned.

It will readily be understood that the reaming action on the bowl of a tobacco pipe performed by my reamer assembly is particularly advantageous both from the operative and the structural viewpoint. On one hand it gives the desired relative rotation between the pipe bowl and the reaming tool without the awkward physical movement on the part of the user which is required if the bowl of a tobacco pipe be rotated on a stationary reaming tool. On the other hand, the simple structure involved in the rotatable mounting of the reaming tool avoids the tendency to early mechanical failure which may be met if complex power-transmitting elements be included in a device of this sort.

In the modified form of my pipe reamer shown in Figs. III and IV of the drawings the horizontal arm 4 of Figs. I and II is replaced by a shallow cup or pan 12 which serves completely to cover and hide the interior of the dish 13. Pan

3

12, which serves as a receptacle for pipes, pipe cleaners and the like, is rotatably mounted on upright post 14 by rigid connection with spindle 15 which is rotatable in the post. Convenient means for mounting post 14 in dish 13 are shown as a nut 14a on a threaded extension 14b of post 14 and bearing against a washer 14c on the under surface of the dish. Reaming tool 16 is mounted on pan 12 in a position substantially removed from the center of rotation of the pan so that the same simple crank motion of the user's arm which reams out a pipe bowl in the form of the device shown in Figs. I and II serves to perform an identical function in the modification of Figs. III and IV.

As in the simpler form of the device shown in Figs. I and II, means to prevent the scattering of pipe refuse desirably are provided in the modified reamer of Figs. III and IV. Such means comprise a circular guard or cup 17, which as shown is made integral with the bottom of pan 12, and which itself is bottomless to permit refuse from the pipe to fall into the underlying dish 13. The reaming tool 16 is mounted in upright position within cup 17 on a spider 18 which is welded to or otherwise suitably supported by the bottom of the pan at the edge of the opening bounded by the peripheral wall of the cup.

The modified form of my pipe reamer shown in Fig. V of the drawings is the same as that shown in Figs. I and II except that the openings 10 in the bottom of the cup are omitted and hence the discharge of refuse from the pipe is retained in the cup.

Thus reference numeral 18 designates a relatively deep dish, which serves as a mounting base for the mechanical elements of the reamer and also as a receptacle for pipes, pipe cleaners and the like. Secured in the bottom of the dish 18 there is an upright post 19, which desirably is mounted centrally of the dish, as shown, and which houses a spindle 20. Convenient means for mounting post 19 in dish 18 is shown as a nut 21 on a threaded extension 22 of post 19 and bearing against a washer 23 on the under surface of the dish. A horizontal tool-carrying arm 24 is mounted on spindle 20, being shown as secured thereto by means of a cap 25 threaded at 26 to the upper region of the spindle. The ball 27 shown as mounted on the tool-carrying arm 24 is purely ornamental.

The reaming tool 28 is non-rotatably mounted in upright position on horizontal arm 24 in a position substantially removed from the vertical pivot provided by spindle 20 so that the same simple crank motion of the user's arm which reams out a pipe bowl in the form of the device previously described serves to perform an identical function in the modification of Fig. V.

As in the previously described forms of the device, means to prevent scattering of pipe refuse desirably are provided in the modified reamer of Fig. V. Such means comprise a circular guard or cup 29 mounted on the tool-carrying arm 24 around the reaming tool 28. The cup 29 is provided with an imperforate bottom 30 and hence the cup also functions as a receptacle for ashes and dottle from the tobacco pipes in the bowls of which the reamer acts. The spindle 20 is readily removable from the post 19 and hence the cup 29 may be separated from the dish 18 and emptied when desired. If desired, a grid 31 may be provided in the dish 18.

In the modified form of my pipe reamer illustrated in Fig. VI of the drawings, the horizontal

4

arm 24 and cup 29 of Fig. V are replaced by a relatively large cup 32 having a bottom 33, preferably, but not necessarily, having a diameter slightly greater than the radius of the dish 34. The cup 32 provides a means for preventing scattering of pipe refuse as do the similar cup elements previously described.

The bottom 33 of the cup 32 is provided adjacent the periphery thereof with an internally threaded boss or tubular projection 35 adapted to receive for rigid connection therewith threaded end 36 of spindle 37 which is rotatable in the post 38. Convenient means for mounting post 38 in dish 34 are shown as a nut 39 on threaded extension 40 of post 38 and bearing against a washer 41 on the under surface of the dish.

The reaming tool 42 is non-rotatably mounted in upright position on the bottom 33 of the cup 32 in a position substantially removed from the vertical pivot provided by spindle 37, preferably, but not necessarily, centrally of the bottom 33, so that the same simple crank motion of the user's arm which reams out a pipe bowl in each form of the device previously described serves to perform an identical function in the modification of Fig. VI.

The bottom 33 of the cup 32 is imperforate as illustrated in Fig. VI and hence the cup 32 performs a dual function in that it not only provides a rotatable supporting member for the reaming tool 42, but also functions as a receptacle for ashes and dottle from the tobacco pipes. The spindle 37 is readily removable from the post 38 and hence the cup may be readily separated from the dish 34 and emptied when desired.

The dish 34 serves not only as a mounting base for the mechanical parts of the reamer, but also as a receptacle for pipes, pipe cleaners and the like.

If desired, the bottom 33 of the cup 32 may be provided with openings such as the openings 10 of Figs. I and II, in which case the dish 34 will serve as a receptacle for the ashes and dottle from the tobacco pipes as previously described in connection with the forms of the device of Figs. I to IV.

In the modified form of my pipe reamer shown in Fig. VII of the drawings the rotatable supporting member for the reaming tool consists of a shallow cup or pan 43 having an imperforate bottom 44 and normally positioned above and spaced from a relatively shallow dish 45. The pan 43, which in this instance serves also as a receptacle for the ashes and dottle from the tobacco pipes, is rotatably mounted on upright post 46 by rigid connection with spindle 47 which is rotatable in the post. Convenient means for mounting post 46 in dish 45 are shown as a nut 48 on a threaded extension 49 of post 46 and bearing against a washer 50 on the under surface of the dish.

Reaming tool 51 is non-rotatably mounted in upright position on pan or cup 43 in a position substantially removed from the center of rotation of the pan so that the same simple crank motion of the user's arm which reams out a pipe bowl in each form of the device previously described serves to perform an identical function in the modification of Fig. VII.

The dish 45 serves not only as a mounting base for the mechanical parts of the reamer, but also as a receptacle for pipes, pipe cleaners and the like.

It may be explained that in all modifications of the invention the structure of the reamer assembly may be primarily or wholly of metal in accordance

with the implications of the foregoing description and drawings. It is, however, possible that all elements of the structure may be made of suitable non-metallic material such as molded plastic, with such change in the detailed structure of the reamer assembly as the use of such alternative material will indicate.

Having illustrated an exemplary embodiment of my invention and modifications thereof, I wish it to be understood that various other modifications in form and arrangement may be made while remaining within the bounds of my invention as defined in the claims appended hereto.

This application is a continuation-in-part of my copending application Serial No. 570,544, filed December 30, 1944, now abandoned.

I claim as my invention:

1. A pipe-reamer assembly comprising an upwardly open receptacle, a pivot post supported by and extending upwardly in said receptacle, a tool-carrying member horizontally extending from and rotatable with respect to said post, and a reaming tool carried non-rotatably by said tool-carrying member in a position removed from the center of rotation of the said tool-carrying member and within the horizontal bounds of the receptacle, so that crank motion applied to the said reaming tool through the bowl of a pipe causes the tool to move circularly about the pivot post with relative movement between the tool and the pipe bowl to remove from the latter refuse which falls into the receptacle.

2. A pipe-reamer assembly in accordance with the statement of claim 1 in which the rotatable tool-carrying member is in the form of a pivotally mounted horizontally extended arm.

3. A pipe-reamer assembly in accordance with the statement of claim 1 in which the rotatable tool-carrying member is in the form of relatively shallow rotatably mounted pan having the reaming tool mounted non-rotatably therein in a position removed from the center of rotation of the said pan.

4. A pipe-reamer assembly comprising an upwardly open receptacle, a pivot post supported by and extending upwardly in said receptacle, a tool-carrying member horizontally extending from and rotatable with respect to said post, a reaming tool rotatable relative to said post and carried non-rotatably by said tool-carrying member in a position removed from the center of rotation of the said tool-carrying member and within the horizontal bounds of the receptacle, so that crank motion applied to the said reaming tool through the bowl of a pipe causes the tool to move circularly about the pivot post with relative movement between the tool and the pipe bowl to remove from the latter refuse which falls into the receptacle, and a refuse-retaining guard surrounding the reaming tool to prevent accidental scattering of refuse from the bowl of the pipe.

5. A pipe-reamer assembly in accordance with the statement of claim 4 in which the rotatable tool-carrying member is in the form of a pivotally mounted horizontally extended arm.

6. A pipe-reamer assembly in accordance with the statement of claim 4 in which the rotatable tool-carrying member is in the form of a relatively shallow rotatably mounted pan having the reaming tool mounted therein in a position removed from the center of rotation of the said pan and the pan being perforate in a region surrounding the said reaming tool and within the said refuse-retaining guard.

7. A cleaner for a pipe comprising a reaming

tool, a supporting member for said tool, means for rotatably mounting the supporting member and reaming tool on an ash receptacle so that the reaming tool is in offset relation to the axis of

5. rotation of the supporting member and in such relation to said ash receptacle as to locate all portions of the reaming tool within the horizontal bounds of the receptacle, said supporting member being rotatable by moving a pipe bowl against said tool with the tool mounted in the cavity of the pipe bowl.

8. A pipe-reamer assembly comprising an upwardly opening receptacle, means comprising a tool-carrying member supported by said receptacle, means for rotatably mounting said tool-carrying member, and a reaming tool carried non-rotatably by said tool-carrying member in a position removed from the center of rotation of said tool-carrying member so that crank motion applied to the said reaming tool through the bowl of a pipe causes the tool to move circularly with relative movement between the tool and the pipe bowl to remove from the latter refuse which falls into the receptacle.

9. A cleaner for a pipe comprising a reaming tool, a supporting means for non-rotatably carrying said tool, and means for non-rotatably mounting the supporting means on an ash receptacle so that the reaming tool is in offset relation to the axis of rotation of the supporting means, said supporting means being rotatable by moving a pipe bowl against said tool with the tool mounted in the cavity of the pipe bowl.

10. A cleaner for a pipe in accordance with the statement of claim 9 in which the rotatable supporting means comprises a cup, and the reaming tool is mounted non-rotatably in said cup.

11. A pipe-reamer assembly comprising a mounting base, an upright pivot post supported by said mounting base, a tool-carrying means horizontally extending from and rotatable with respect to said post, and a reaming tool carried non-rotatably by said tool-carrying means in a position removed from the center of rotation of the said tool carrying means, so that crank motion applied to the said reaming tool through the bowl of a pipe causes the tool to move circularly about the pivot post with relative movement between the tool and the pipe bowl to remove refuse therefrom.

12. A pipe-reamer assembly in accordance with the statement of claim 11 in which the tool-carrying means comprises a cup, and the reaming tool is mounted non-rotatably in said cup.

13. In a pipe-reamer assembly, the combination comprising, a spindle mounted on a base structure, a supporting member rigidly connected to and extending outwardly from said spindle and a reaming tool non-rotatably connected to said supporting member, the axis of said reaming tool being spaced from the axis of said spindle.

14. A pipe reamer assembly comprising a mounting base, a tool-supporting means, upright mounting means rotatably mounting said tool-supporting means on said mounting base for rotation about a vertical axis, said supporting means extended outwardly from the axis of rotation thereof, a reaming tool non-rotatably carried by the said supporting means in off-set relation to the axis of rotation of the supporting means, said supporting means being rotatable by moving a pipe bowl against said tool with the tool in the cavity of the pipe bowl.

15. A pipe reamer assembly in accordance with

7 the statement of claim 14 in which the rotatable tool-carrying means is in the form of a pivotally mounted horizontally extended arm.

16. A pipe reamer assembly in accordance with the statement of claim 14 in which the rotatable tool-carrying means is in the form of a pan having the reaming tool mounted non-rotatably therein in a position removed from the axis of rotation of the said pan.

17. A pipe reamer assembly in accordance with the statement of claim 14 in which the rotatable tool-supporting means comprises a cup, and the

reaming tool is mounted non-rotatably in said cup.
